SIGNALING DEVICE FOR LOOMS
AND THE LIKE

George Frank League, Greenville, S. C.

Application October 29, 1951, Serial No. 253,705

2 Claims. (Cl. 116—132)

1

This invention relates to a signalling device or indicator and more especially to an improved signalling device adapted to be mounted on a machine, such as a loom or the like, and having manually movable means which may be manipulated to vary the attitude of the movable means to indicate that a particular machine is not operating satisfactorily.

Heretofore, it has been the practice in many textile plants to use loose objects or loose parts of a machine which were conspicuously positioned by the operator of the machine to serve as a warning to the mechanic or fixer of the machine that it was not operating satisfactorily. This makeshift practice has proved expensive due to the fact that the vibration of an operating machine has often caused the parts used as an indicating medium to fall into the machine thus resulting in damage to the machine as well as the parts utilized as a signalling device. Also, the parts heretofore used as a signalling device have fallen to the floor, in many instances, resulting in damage to the parts as well as to the floor.

Another objection to the types of signalling devices heretofore employed is that such signalling devices have lacked in uniformity and have not clearly indicated the particular part of the machine which may not be operating satisfactorily.

It is, therefore, the primary object of this invention to provide an improved signalling device or indicator for summoning operators or an appropriate workman when repairs are required to textile machinery or when a particular machine is not operating satisfactorily and having means associated with the signalling device for specifically designating the nature of the repairs to be made.

It is another object of this invention to provide an improved signalling device comprising a standard which may be secured to a relatively high or conspicuous portion of a textile machine, such as a loom or the like, and the standard being provided with a notch or slot in the upper end thereof in which a plurality of rigid vanes, leaves or flags of different colors are disposed. The standard has a pivot pin or shaft therein and each of the flags has a longitudinally extending slot therein slidably penetrated by the pivot pin for supporting the flags. The bottom of the notch in the standard is provided with a wedge-shaped projection and the lower end or bottom of each of the vanes is provided with at least one inverted substantially V-shaped notch which fits

over the wedge-shaped projection in the bottom of the notch in the standard for holding the vanes or flags in an upright position. Thus, the flags may be raised out of engagement with the wedge-shaped projection and normally permitted to depend from the pivot pin in order to project downwardly and outwardly at an angle when the machine is operating satisfactorily and, upon the occurrence of an adverse condition of the machine, the flag of the desired color may be positioned in an upright position to thus indicate to a particular class of workmen that the adverse condition exists.

It is still another object of this invention to provide an improved signalling device comprising a standard, on one vertical face of which a plurality of parallel superposed rows of indicia are provided and wherein each row of indicia indicates a particular element or combination of elements on the machine. The standard is provided with a row of holes or cavities, there being at least one of these holes adjacent each of the rows of indicia, and a suitable indicating element, such as a pin or peg, may be inserted in any one of the cavities to thereby indicate to the repair-man the particular element or combination of elements on a machine which may not be functioning properly.

Some of the objects of the invention having been stated, other objects will appear as the description proceeds when taken in connection with the accompanying drawings, in which—

Figure 1 is a front elevation of the improved signalling device mounted on a part of a textile machine such as the arch of a loom and showing all of the vanes or flags in a vertical or raised position;

Figure 2 is an elevation looking at the right-hand side of the signalling device shown in Figure 1 but being shown at a reduced scale and showing some of the flags or vanes in a lowered position and showing the arch of the loom in cross-section;

Figure 3 is a fragmentary elevation similar to the upper portion of Figure 2 with parts broken away and showing a modified form of vane or flag mounted on the standard;

Figure 4 is an enlarged elevation showing one of the modified forms of vanes or flags disassociated from the standard.

Referring more specifically to the drawings, the original form of the invention is shown in Figures 1 and 2 wherein the improved signalling device is shown mounted on a portion of a textile machine such as the arch of a loom indicated

2

at 10. The signalling device comprises a standard or upright member, broadly designated at 11, which may be of any desired shape in cross-section but is preferably provided with a flat front face 12. This vertical or front face 12 is provided with a legend in the form of a plurality of vertically spaced items or horizontal rows of indicia thereon, wherein each horizontal row identifies a particular element or combination of elements on the particular machine on which the signalling device is mounted. The standard 11 may be secured to the arch 10 by any suitable means such as a bolt 13. The upper portion of the standard is provided with a slot defined by side walls 14 and 15 and the bottom of this notch has a projection 16 integral therewith which is preferably wedge-shaped or triangularly-shaped and the sharp edge of which faces upwardly.

A plurality of substantially rigid vanes, leaves or flags, designated generally at 17, of varying lengths are slidably mounted between the side walls 14 and 15 on a shaft 18 which is shown in the form of a rivet carried by the side walls 14 and 15. There are four flags shown in Figures 1 and 2 which are indicated individually at 17a, 17b, 17c and 17d. The lower portion of each of the flags or vanes 17 has a vertically or longitudinally extending slot 19 therein which is slidably penetrated by the shaft 18 to thus permit each of the vanes or flags 17 to be raised and lowered on the pivot shaft 18 and to also be pivoted thereon. The lower edge of each of the vanes or flags 17, when in the vertical or upright position in which the vane 17a is shown in Figure 1, is provided with an inverted substantially V-shaped or triangular notch therein which is engaged by the projection 16 to maintain the corresponding flag or vane in a vertical or upright position.

When any one or more of the flags or vanes 17 are in the upright position, since the flags or vanes 17 are of different colors, each of the different flags will indicate that different types of classes of repairs need to be made on the machine so the repair-man is advised in advance of approaching machine as to the type of equipment which will be required to repair the machine or, if several different repair-men perform a different class of repairs on each machine, the particular flag or vane 17 which is in the upright position will serve as an indicator as to which class of repair-man is required to repair the machine.

The flags or vanes 17 are of varying lengths to enable the operator of the machine to easily grasp the flags independently of each other for raising and lowering the same although they may be disposed in horizontal alignment with each other. Also, by providing flags or vanes of varying lengths, it is possible for the operator to position more than one flag in an upright position to indicate that more than one class or type of repair must be made to the machine.

It will be observed in Figure 2 that the standard 11 is provided with a vertically extending row of cavities or bores 21 in one side thereof, there being one of these bores provided in the horizontal plane of each of the vertically arranged horizontal rows of indicia provided on the face 12 of the standard 11. If so desired, this row of cavities 21 may be provided in the face 12 on which the indicia appears, however, this row of cavities is shown in face of the standard adjacent the face 12 on which the indicia is provided.

When the operator raises any one or more of

the vanes or flags 17 from the inclined position, in which the vanes 17b, 17c and 17d are shown in Figure 2, to the upright position, he may also insert a suitable indicating element, such as a peg or pin 22, in any one or more of the cavities 21. This pin will coincide with the particular row of indicia defining the particular element or combination of elements which may be functioning improperly on the machine. Thus, in addition to summoning the proper class of repair-men upon raising the appropriate flag or vane 17 to the upright position, the repairman will also be advised as to the particular element or combination of elements on the machine which are not operating satisfactorily upon reaching the machine.

The particular indicia shown on the face 12 of the standard 11 in Figure 1 is arranged in order to use the signalling device on a loom. However, it is to be understood that other indicia may be provided on the face 12 of the standard 11 in the event that the improved signalling device is used with other types of machines such as spinning frames, carding machines and the like.

It is thus seen that, in order to lower any one of the flags or vanes 17 from the upright position in which vane 17a is shown in Figure 1 to the inclined position in which the vanes 17b, 17c and 17d are shown, it is merely necessary for the operator to raise the corresponding flag or vane 17 sufficiently so the inverted V-shaped notch 20 at the lower edge thereof will clear the wedge-shaped projection 16 in the bottom of the notch defined by the walls 14 and 15, after which the operator may swing the corresponding vane or flag 17 in either direction about the pivot shaft 18 to permit the corresponding side edge of the flag or vane 17 to rest upon the wedge-shaped projection 16 while in the inclined position. Of course, it is merely necessary to reverse this procedure when it is necessary to raise one or more of the flags or vanes 17 to the upright position.

Modified form of flag or vane structure

Referring to Figures 3 and 4, there is shown a modified form of flag or vane structure embodied in each of the vanes, each of these modified vanes being generally designated at 17'. There are four of these vanes shown in Figure 3 which are indicated individually at 17a', 17b', 17c' and 17d'. These vanes 17' are supported in the identical manner in which the vanes 17 are supported and corresponding parts shown in Figure 3 shall bear the same reference characters as those shown in association with the original form of the invention with the prime notation added.

In view of the fact that the varying lengths of the vanes 17 shown in Figures 1 and 2 will permit a flag disposed in back of another flag to be observed from only one side of the signalling device, the modified form of vane is particularly provided to expose a substantially greater portion of a vane or flag 17' disposed rearwardly of another vane or flag to the view of an operator or repair-man than is the case in the type of vane or flag structure shown in Figures 1 and 2. To this end, the modified form of vanes or flags 17' are each provided with a pair of laterally spaced diverging slots or notches 25 and 26 in the lower edge thereof, each of which is an inverted substantially V-shaped notch.

It will be noted that the notches 25 and 26 are positioned at opposite sides of the longitudi-

nal center of each of the vanes 17' and are shaped to conform to the shape of the wedge-shaped projection 16' on the standard 11'. Also, the slot 19' is alined with the longitudinal center of each vane. Thus, by positioning a pair of the vanes, such as the vanes 17a' and 17b', in a substantially upright position with the vane 17a' having its notch 25 in engagement with the projection 16' and the vane 17b' having its notch 26 in engagement with the wedge-shaped projection 16', the substantially upright flags 17a' and 17b' will then be disposed in slightly staggered relation to each other so that both of the flags may be observed from either side of the signalling device. Inasmuch as the flags 17' are of different colors, this will indicate that two different classes of repair-men are required to perform repairs on the machine or that two different classes of repairs are to be made on the machine.

It is thus seen that I have provided a novel signalling device which may be economically constructed from materials which are readily available such as wood, plywood, fiber board or the like, and which signalling device may be operated easily without the possibility of any of the flags or vanes 17 or 17' which are in the upright position falling to the inclined position shown or injuring either the signalling device or the machine.

It is evident that a signalling device of this character will save considerably in the cost of operating a large plant since the signalling device will indicate that a particular machine is operating improperly and will also indicate the nature of the repairs to be made on the machine so the operator of the machine will not be interrupted when operating the machine or other machines.

Also, when a single operator operates a relatively large number of machines, it may be difficult for the operator to remember the reason why a particular machine is not operating satisfactorily without investigating the same very carefully and it is evident that such a procedure is unnecessary with the present signalling device.

In the drawings and specification, there has been set forth a preferred embodiment of the invention and although specific terms are employed, they are used in a generic and descriptive sense only and not for purposes of limitation, the scope of the invention being defined in the claims.

I claim:

1. An improved signalling device comprising a standard adapted to be mounted on a machine and having a pair of oppositely spaced side walls on the upper end thereof defining a groove, an upwardly extending projection in the bottom of said groove and extending between said side walls, a pivot shaft spaced substantially above said projection and carried by and extending between the spaced side walls, a plurality of sub-

stantially rigid flags of varying lengths slidably mounted between said side walls and each being provided with a longitudinally extending slot intermediate the upper and lower ends thereof which is slidably penetrated by the pivot shaft, each of said flags having a plurality of notches in the lower edge thereof each conforming substantially to the shape of said projection in the bottom of the groove in the upper end of said standard, and said flags being of different colors whereby flags may be raised selectively relative to said pivot shaft sufficiently to clear the upper end of said projection and then pivoted about said pivot shaft to assume an inoperative position and any one of said flags may be maintained in the raised position by positioning a selected notch in the lower end of the corresponding flag in engagement with the projection on the bottom of said groove to maintain the flag in the raised position to thereby serve as a signal.

2. An improved signalling device adapted to be mounted on a machine comprising a standard having a pair of oppositely spaced side walls projecting from the upper end thereof and defining a groove therebetween, a projection in the bottom of said groove and extending between said side walls, a pivot shaft spaced substantially above said projection and carried by said side walls, a plurality of vanes disposed between said spaced side walls and each being provided with a longitudinally extending slot therein, said longitudinally extending slot being disposed substantially centrally of each of the vanes with respect to opposite side edges of the vanes, a pair of laterally spaced notches in the lower edge of each of said vanes disposed substantially equidistant from opposite sides of the longitudinal center of each of said vanes, each of said notches in each vane conforming substantially to the shape of the projection in the bottom of said groove in the standard, and said vanes being of different colors, whereby said vanes may normally assume an inclined position with their side edges resting upon the projection on the bottom of said groove and, when desired, as many as two of the vanes may be pivoted about said pivot pin and raised sufficiently so their bottom edges will clear the projection as they are pivoted about the pivot shaft and then the latter vanes may be lowered to position opposite notches in the two vanes in engagement with the projection in the bottom of said groove to thereby cause the two vanes to extend at slight angles with respect to each other and whereby the two raised vanes may be observed from opposite sides of the signalling device.
